METHOD OF REFRIGERATION

Filed Nov. 20, 1929

INVENTOR

Bo Foike Randel

UNITED STATES PATENT OFFICE

BO FOLKE RANDEL, OF SAN DIEGO, CALIFORNIA

METHOD OF REFRIGERATION

Application filed November 20, 1929. Serial No. 408,467.

My invention relates to refrigerating method and the objects thereof are: First, to provide for the introduction of a liquefied refrigerating medium inert to a liquid medium into said liquid medium, said liquid medium being under internal pressure sufficiently low to cause the evaporation of the introduced liquefied refrigerating medium forming spaces or volumes of vapor during its passage through said liquid, then causing diffusion of vapors of said liquid into said spaces or volumes of vaporized refrigerating medium, with the removal of heat; Second, to provide general circulation through the apparatus by the means of a pump; Third, to devise a method of refrigeration where the working pressures are comparatively low, permitting low cost of manufacture and operation.

With these and other objects in view as will appear hereinafter, my invention consists of a certain novel method to produce refrigeration and certain arrangement of parts in an apparatus to accomplish this method of refrigeration as will hereinafter be described in detail and particularly set forth in the appended claims, reference being had to the accompanying drawing and to the characters of reference thereon which form a part of this application in which:

Fig. 1 is a diagram illustrating the scientific principles upon which my method of refrigeration is based, and Fig. 2 is a diagrammatic view of arrangement of the apparatus in which my method of refrigeration is carried out.

In Fig. 1, assume a vessel L connected at the upper end to a pump through a pipe D. The lower end of this vessel is fitted with an inlet pipe C, the fluid entering through this pipe being controlled by a valve E. The vessel is filled with a liquid to level S.

As an illustration, it is assumed that the liquid in vessel L is water and that the fluid entering through C is liquid pentane. Also, that the pump maintains a pressure at A of 3 pounds absolute or a vacuum of 23.81 inches of mercury.

It is assumed that the pentane entering through valve E is under sufficient pressure to retain it in liquid form, and a 10 pounds

absolute pressure, under normal temperature, will be sufficient to do so.

It is seen that the pentane liquid entering into the water will form continuous drops at M, which, due to the lower specific gravity of pentane, will rise upwards through the water. It is assumed that the pressure due to the height of water from the surface S to a point B plus the external pressure at surface S is sufficient to keep the drops of pentane in liquid form until point B is reached, but that at this point B the pressure is so reduced as to cause the pentane liquid to expand and vaporize, forming gas bubbles. In the illustration, it is assumed that F and G are drops of liquid pentane; at H vaporization begins; at I this vaporization continues; at J and K are bubbles of pentane gas, gradually growing larger as they pass upwards through the water.

Now, since water and liquid pentane are mutually immiscible liquids, as long as the pentane remains in the liquid form water cannot enter into union with same. However, as soon as this pentane begins to take vapor form, water will enter into the resultant bubble and will diffuse in the form of water vapor into the space provided by the vaporized pentane. There is no union of the two vapors, but a diffusion of one into the other, each filling the entire space.

Further, when the water vapor enters into the space provided by the pentane bubble, it will enter as into an absolute vacuum, the liquid pentane containing no water and therefore, when expanding into vapor form, being absolutely devoid of water vapors.

The effect of this action will be double. First, removal of heat and reduction of temperature as a result of pentane expanding into vapor form, and second, as a result of water vaporizing into a vacuum. Pentane will vaporize at 3.34 pounds abs. pressure and 32 degrees F., and similarly, water will vaporize into an absolute vacuum at 32 degrees F. The vaporization of the pentane will remove 160 B. t. u., and the vaporization of the water, approximately 1000 B. t. u. per pound vaporized.

If a lower temperature than 32 degrees F. 100

is desired, I substitute for the water a solution of a gas in a liquid. As an illustration, I select ammonia absorbed in water.

The introduction of liquid pentane in a concentrated solution of ammonia in water, and under pressure conditions such as to cause vaporization of the liquid pentane into vapor form, will result in the diffusion of both ammonia and water vapors into the space provided by the vaporized pentane. And when ammonia vaporizes from a solution of ammonia and water into an absolute vacuum, the resultant heat transfer is approximately 800 B. t. u. per pound and with a possible temperature reduction down to 40 degrees F. below zero.

In the above description, water and pentane liquids have been mentioned as mutually immiscible liquids. This statement is true from a practical standpoint only, as a very small percentage of pentane liquid will be absorbed in the water. This fact, however, does not materially affect the operation of my method, and I may employ in this method liquids which are miscible in all proportions.

In Fig. 2, I illustrate one form in which the apparatus for carrying out my method of refrigeration may be arranged. In this Fig. 2, which is a diagrammatical view of the arrangement of parts, 1 is the pressure chamber, 2 vacuum or suction chamber, 3 condenser, 4 receiver for liquid refrigerant, 5 heat exchanger, 6 evaporator, 7 refrigerating coils, 8 liquid refrigerant drop former, 9, 10, and 11 control valves.

The different parts of the apparatus necessary to carry out my method of refrigeration are conventional and well known in the arts and may be constructed and arranged in many different ways. Condenser may be either air- or water-cooled. As illustrated, condenser is equipped with fins 3a for air-cooling. Means of producing circulation throughout the apparatus may be as shown, or any conventional vacuum pump; piston, rotary, gear, or jet pump, may be used. In the illustration, I show a common liquid jet pump, with a centrifugal pump 1c driven by motor 1d forcing the liquid through jet nozzle 2a and ejector nozzle 2b, causing a lowering of the pressure in chamber 2 and a raising of the pressure in chamber 1, due to the accumulation of vapors and liquid drawn in from chamber 2.

Similarly, other parts of the apparatus, as evaporator, refrigerating coils, heat exchanger, liquid receiver, etc., may be constructed in many different forms, and I do not limit myself to any definite form of construction.

Using the arrangement and construction as shown diagrammatically in Fig. 2 as an illustration of the operation of my method, it is seen that the action of pump 1c in conjunction with the manipulation of control valves

9 and 10 will establish two differential pressure zones. Low pressure zone will include chamber 2, pipe 6b, evaporator 6, refrigerating coil 7, pipe 7a, and inner pipe 5b of heat exchanger 5. High pressure zone will include chamber 1, condenser 3, receiver 4, outer shell 5a of heat exchanger 5, pipe 5c up to control valve 9, and pipe 1f up to control valve 10.

This dividing into two pressure zones will cause a general circulation as indicated by arrows as follows: Vapors from evaporator 6 through 6b to chamber 2, and thence through ejector to high pressure zone in chamber 1. Liquid from evaporator 6 through refrigerating coils 7, inner pipe 5b of heat exchanger and 7a to chamber 2, thence together with the vapors from pipe 6b through ejector 2b into high pressure zone in chamber 1. The proportion of liquids allowed to pass from evaporator 6 through pipe 7a to vapors passing from evaporator 6 through pipe 6b is controlled by valve 11 in pipe 7a, so as to maintain a liquid level at 6a. The liquid level at 6a may also be automatically controlled by a float valve.

There is also a circulation of liquid from receiver 4 through 4a, 5a, 5c, and valve 9 into liquid refrigerant drop former 8 and finally into evaporator 6. Said drop former may be a funnel-shaped and perforated vessel, through which the liquid will pass, forming drops, which pass upwards through liquid in evaporator 6. Also, a circulation of liquid from chamber 1 through pipe 1f and valve 10 into evaporator 6.

The action in evaporator 1 has been described in the description of the principle upon which my method is based, as illustrated in Fig. 1. It will be further described as follows:

While many different mediums may be used in my method, I choose as illustration pentane and water. The pressure in evaporator is maintained at approximately 3 pounds abs. at surface 6a. Liquid in receiver 4 is assumed to be liquefied pentane under a total pressure of 15 pounds absolute in chamber 1. This total pressure is assumed to be made up of 11 pounds on pentane and 3 pounds on water vapor.

The liquid pentane will now enter through drop former 8 into the water, and, as described previously, will expand and vaporize as soon as a point is reached in the upward path where the pressure is low enough to allow such vaporization. Immediately upon vaporization, the space provided will permit the diffusion of water vapor into the vaporized pentane.

The resultant mixture of water and pentane vapors will be drawn through pipe 6b, chamber 2, ejector nozzle 2b, into pressure chamber 1. In this chamber, the water vapor will condense; in fact, the water vapor will

begin to condense in the passage through the ejector as soon as coming in contact with the water from jet nozzle 2a. In condensing the water vapor, the pentane vapor will gradually accumulate and increase in pressure until this vapor will also condense in condenser 3 and collect in liquid form in receiver 4. The temperature in chamber 1, due to the condensing of the water vapor, will be maintained sufficiently high to prevent the condensing of the pentane vapor in this chamber, the cooling and liquefying being done in condenser 3. If some water vapor should condense in condenser 3, it will be driven into evaporator ahead of liquid pentane, and will not interfere with the operation.

The cooled water in evaporator 6 is permitted to pass through refrigerating coils 7, and thence back to chamber 1.

If a solution of a gas in a liquid is used, as ammonia in water, the action will be similar to the above described. The drops of liquid pentane will form as above in a rich solution in evaporator 6. These drops will expand into vapor form when the point of sufficiently low pressure is reached; and into the spaces or volumes now formed the ammonia will diffuse, with removal of heat and reduction of the temperature and the lowering of concentration of the solution. The mixture of ammonia and pentane vapors will pass through 6b and suction chamber 2 to pressure chamber 1. The mixture will meet the weak solution coming from evaporator through 7a, and the ammonia will be reabsorbed by same, the pressure being sufficiently increased to allow this, while the pentane will liquefy in condenser and collect in receiver 4. As the pressure in chamber 1 is comparatively low, the ammonia vapor can not liquefy, but will remain in vapor form, except that part of this vapor will be absorbed in the weak solution coming through pipe 7a. Baffle plates 1a in chamber 1 will assist in thoroughly mixing liquid and vapors and cause rapid absorption.

Having thus described my invention, what I claim as new and desire to secure by Letters Patent is:

1. A method of refrigeration wherein a liquefied refrigerating medium is introduced into a solution of a gas absorbed in a liquid, said solution being chemically inert towards said refrigerating medium and substantially immiscible with said refrigerating medium in the liquid state, reducing the pressure on said solution so that the said liquefied refrigerating medium during the passage through said solution will expand and vaporize and form spaces or volumes of vapor in said solution, separating the absorbed gas from said solution by the diffusion of said absorbed gas into said spaces or volumes of vaporized refrigerating medium, the vaporization of said liquefied refrigerating medium, the vaporization of said

liquefied refrigerating medium and the separation of said absorbed gas from said solution being accompanied by the absorption of heat.

2. A method of refrigeration wherein a liquefied refrigerating medium is introduced into a solution of a gas absorbed in a liquid, said solution being chemically inert towards said refrigerating medium and substantially immiscible with said refrigerating medium in the liquid state, reducing the pressure on said solution so that the said liquefied refrigerating medium during the passage through said solution will expand and vaporize and form spaces or volumes of vapor in said solution, separating the absorbed gas from said solution by the diffusion of said absorbed gas into said spaces or volumes of vaporized refrigerating medium, the vaporization of said liquefied refrigerating medium and the separation of said absorbed gas from said solution being accompanied by the absorption of heat, then separating the vapor of said refrigerating medium from said gas by condensing said vaporized refrigerating medium back to liquid state and reabsorbing said gas into said liquid, reforming a solution of the said gas in said liquid.

3. A method of refrigeration wherein a liquefied refrigerating medium is introduced into a solution of a gas absorbed in a liquid, said solution being chemically inert towards said refrigerating medium and immiscible with said refrigerating medium in the liquid state, reducing the pressure on said solution so that the said liquefied refrigerating medium will expand and vaporize and form spaces or volumes of vapor in said solution, separating the absorbed gas from said solution by the diffusion of said absorbed gas into said spaces or volumes of vaporized refrigerating medium, the separation of said absorbed gas from said solution being accompanied by the absorption of heat.

4. A method of refrigeration wherein a liquefied refrigerating medium is introduced into a solution of a gas absorbed in a liquid, said solution being chemically inert towards said refrigerating medium and immiscible with said refrigerating medium in the liquid state, reducing the pressure on said solution so that the said liquefied refrigerating medium will expand and vaporize and form spaces or volumes of vapor in said solution, separating the absorbed gas from said solution by the diffusion of said absorbed gas into said spaces or volumes of vaporized refrigerating medium, the vaporization of said liquefied refrigerating medium and the separation of said absorbed gas from said solution being accompanied by the absorption of heat, then separating the vapor of said refrigerating medium from said gas by condensing said vaporized refrigerating medium back to liquid state and reabsorbing said gas into

said liquid, reforming a solution of the said gas in said liquid.

5. A continuous operating method of refrigeration which comprises introducing an inert and immiscible liquid in a body of a liquid refrigerating medium, reducing the pressure sufficient to vaporize the inert liquid as it passes through the refrigerating medium creating spaces in said body of refrigerating medium diffusing vapors of said refrigerating medium into said spaces forming a mixture of vapors, increasing the pressure on said mixture of vapors sufficient to liquefy same, separating the two liquids from each other 10 and returning same to point of beginning, 15 the circulation being caused by mechanical action.

6. Introducing a hydrocarbon liquid into a vessel containing a concentrated solution of 20 NH_4OH and H_2O , lowering the pressure on the solution so as to vaporize the hydrocarbon liquid, as it passes through the said solution and partially decomposing the solution forming free NH_3 gas with resultant absorption 25 of heat.

7. That improvement in the art of refrigeration wherein a liquefied inert gas is forced through a liquid refrigerating agent to evaporate same forming a mixture of vapors; 30 completely separating said inert gas from vapor of said refrigerating agent by condensing both to liquid state, said formed liquids being immiscible and of different specific gravities and wherein circulation of 35 the mediums is caused by mechanical action.

8. Method of refrigeration comprising the creation of spaces of absolute vacuum in relation to a liquid refrigerating medium to cause evaporation of said liquid into said 40 spaces, said spaces of absolute vacuum in relation to the liquid being caused by expanding an inert and immiscible auxiliary liquid into the body of said liquid refrigerating medium, circulation of the mediums being 45 caused by mechanical action.

In testimony whereof, I have hereunto set my hand at San Diego, California, this 12th day of November, 1929.

BO FOLKE RANDEL.
